UNITED STATES PATENT OFFICE.

GOTTHARD J. LEMM, OF TACOMA, WASHINGTON.

SINK STRAINER.

Application filed April 13, 1927. Serial No. 183,291.

This invention relates to devices adapted to close the drain of the sink when it is desired to hold the water therein and to act as a strainer when the water is running freely therethrough. The objects of this invention are: first, to provide a device which will fit in any drain pipe opening of approximate corresponding size; second, which will prevent leakage around the strainer when the 10 said opening is oversize; third, which will provide a suitable bearing to center the disk valve thereof; fourth, which will hold the said disk valve tightly down in place, thus preventing any grit coming between the 15 disk and the strainer; fifth, in which the respective parts may be stamped from sheet metal; and sixth, which is cheap to make and to assemble, easy to operate, and effective in use.

I attain these and other objects by the devices and arrangements illustrated in the accompanying drawings, all made on an enlarged scale, in which:—Fig. 1 is a section of a sink drain showing my improved 20 strainer mounted therein, taken on the line 1—1 in Fig. 2; Fig. 2 is a plan view thereof; Fig. 3 is an elevation of the disk valve; Fig. 4 is an elevation of the strainer, a part thereof being shown in section; Fig. 5 is a 25 plan view of the outer ring; Fig. 6 is an elevation thereof, showing a part thereof in section; Fig. 7 is a section of the spring washer; and Fig. 8 is an elevation of the securing rivet.

Similar numerals of reference refer to similar parts throughout the several views.

In practice, it is found that the diameter of the orifice of the drain pipe 1 varies with comparatively wide limits and therefore, 40 if a strainer is made small enough to enter a smaller such orifice, then there is excessive leakage around such a strainer if inserted in a larger such orifice. Also the flange or shoulder formed in the orifice of the drain pipe 1 is usually very small and the internal diameter thereof may be greater than the external diameter of the strainer and therefore there would be nothing to hold the strainer in place.

I have overcome both of these practical objections by means of the ring illustrated in Figs. 5 and 6. This ring 2 is split as shown in Fig. 6 and is preferably made of 50 spring material and curved to a larger diameter than the maximum allowed for the particular size of strainer. The split is

made with a horizontal portion 3 as shown in said Fig. 6, thereby preventing leakage of water downward through the split. The 60 ring 2 is provided with an inturned flange 4 as shown in the drawings. This ring is manually compressed and forced into the orifice of the drain pipe 1 and rests on the shoulder therein.

The strainer body comprises a plate or disk 5, having openings 6 arranged around its center, and having a downturned flange 7 around its outer circumference. This flange 7 is provided with a wide shallow 70 groove 8 adapted to receive a packing material 9 therein. The center of the disk 5 is depressed or countersunk as shown at 10 in Figs. 1 and 4. This strainer body is inserted into the inside of the ring 2, the packing material 9 filling the space between the ring and the strainer body, thereby preventing any leakage through the space between these parts. The lower edge of the flange 7 of the strainer body rests on top 80 of the flange 4 of the ring 2.

The valve disk 11 is composed of a circular piece of sheet metal having holes 12, corresponding with the above holes 6 in the disk 5 of the strainer body, punched therein. One such hole, however, is punched to bend a part of one side upward to form an operating lug 13. The center of the circular disk 11 is countersunk as shown at 14. The said countersunk portion 14 fits into the 90 countersunk part 10 of the disk 5. A central hole passes vertically through both of the said countersunk portions 10 and 14.

The two parts 5 and 11 are secured together by means of a rivet 15, which passes upward through the holes in the said countersunk parts and which is riveted into the countersunk portion 14 of the disk 11. In practice, however, it is found better to provide a spring pressure between the plates 5 and 11, in order to hold them tightly together and prevent any grit entering between them and yet permitting the disk 11 to have free motion on top of the disk 5. In order to secure this resilience in the simplest and cheapest way I provide a spring washer 16, such as is illustrated in Fig. 7, between the head of the rivet 15 and the lower end of the countersunk part 10 of the disk 5, thus drawing the disk 11 downward thereon.

This spring washer 16 comprises a thin piece of spring material, such as brass, having its outer edge split into sections and rolled back

towards the center to form a circular ring of a substantially circular section and having a hole in its center. When the rivet 15 is inserted through the opening formed by the rolled back outer section of the said washer and through the hole therein to bring its head in contact therewith, and is then passed through the holes in the countersunk parts 10 and 14 and is pressed to compress the said spring washer and is then riveted in the countersunk part 14, the said parts 5 and 11 are securely fastened together with a resilient pressure derived from the compression of said spring washer.

15 Thus it will be seen that I have provided a device which can be fitted into the orifice of any drain pipe of corresponding size and which will be held therein without leakage of any water theremassed, which will be 20 firmly supported within the orifice of the drain pipe, and which will open or close the passage therethrough by the rotation of the disk 11 on the disk 5.

It is, of course, understood that many 25 changes in the details of the construction of such a device may be made without departing from the idea of my invention as outlined in the appended claims.

It is to be understood that, in such 30 cases where the valve action is not desired, the disk 11 may be entirely omitted, in which case the openings 6 in the disk 5 will always permit the water to pass therethrough.

Having therefore described my invention 35 what I claim is:—

1. In a sink strainer, the combination of a 40 split ring adapted to be compressed to fit in the orifice of the drain pipe; a flange extending inward therefrom; a strainer body, comprising a disk having openings therein and a flange around its circumference, said strainer body being adapted to rest on said inward extending flange of said ring; and packing means interposed between 45 said ring and said flange of the strainer body.

2. In a sink strainer the combination of 50 the strainer body comprising a disk having openings therein and with a flange around its circumference; packing means interposed between said flange and the drain pipe; the center of said strainer body disk being countersunk; a valve disk provided with openings therein, corresponding with 55 and complementary to the openings in said strainer body disk; the center of said valve disk being countersunk and fitting in the

countersunk portion of said strainer body disk; a rivet passing through the centers of said countersunk portions and securing the 60 valve disk to the strainer body disk; and a resilient washer interposed between the end of said rivet and said countersunk portion of the strainer body disk.

3. In a sink strainer, the combination of 65 an inward extending split ring flange inserted in the drain pipe and resting on a shoulder formed therein; a strainer body, comprising a disk having openings therein and a flange around its circumference, said 70 strainer body being adapted to rest on said inward extending split ring flange; a valve disk provided with openings therein, corresponding with and complementary to the openings in said strainer body; a riveted pivot means connecting said valve disk to said strainer body disk and adapted to permit the valve disk to turn on the strainer body disk; and spring means interposed between 75 said riveted pivot means and said strainer body disk whereby the valve disk is resiliently held in contact with said strainer body disk.

4. In a sink strainer, the combination of 80 a split ring adapted to be compressed to fit 85 in the orifice of the drain pipe, the surfaces of said ring, at the point of separation, forming a sliding sealed joint; a strainer body comprising a disk having openings therein and a flange around its circumference, said 90 strainer body being adapted to engage and to be supported by said split ring.

5. In a sink strainer, the combination of 95 a strainer body comprising a disk, having openings therein and provided with a downwardly extending circumferentially grooved flange around its periphery; with an inwardly compressible sealing ring adapted to be compressed to fit in the orifice of the 100 drain pipe and lying partially in said circumferential groove in said flange.

6. In a sink strainer, the combination of 105 a strainer body comprising a disk, having openings therein and provided with a downwardly extending circumferentially grooved flange around its periphery; with a self expanding sealing ring adapted to be compressed to enter the orifice of the drain pipe and to expand itself into sealed contact therewith, and extending inward therefrom to fit and support the said strainer body flange.
